UNITED STATES PATENT OFFICE.

ADIEL Y. DODGE, OF SOUTH BEND, INDIANA, ASSIGNOR TO BENDIX BRAKE COMPANY,
OF CHICAGO, ILLINOIS, A CORPORATION OF ILLINOIS.

BRAKE.

Application filed May 22, 1926. Serial No. 110,853.

This invention relates to brakes and is illustrated as embodied in an internal expanding automobile brake of the type in which two or more of the shoes are arranged 5 to overlap each other to give a substantially continuous friction surface in engagement with the drum without the large gaps usually existing between the shoes and brakes.

In one desirable arrangement, the overlapping of the shoes is permitted by providing each of the shoes with a stiffening web which is displaced at one side of the central plane of the shoe, the web for one shoe being on one side of the central plane and the web 10 for the adjacent shoe being on the opposite side so that the webs overlap each other without interference.

I prefer to make these novel shoes of pressed metal parts or stampings generally 20 L-shaped in cross section and which are secured together back to back with the outer flanges forming a substantially cylindrical friction face and with these outer flanges of unequal width to displace the stiffening web 25 as described above.

In one very effective form of the brake, there are at least three shoes, the stiffening web of the central shoe being on the opposite side of the central plane of the brake 30 from the stiffening webs of the end shoes, which therefore can overlap the opposite ends of the stiffening web of the central shoe. The advantages of this arrangement, and various additional features of novelty 35 embodied in the illustrated brake, especially in the construction of the pivoted parts of the shoes, will be apparent from the following description of one illustrative embodiment shown in the accompanying drawings, in which:

Figure 1 is a vertical section through the brake just inside the head of the brake drum and showing the brake shoes in side elevation, the shoes being for convenience shown 45 in applied or "on" position and the cam being shown in "off" position;

Figure 2 is a section on the line 2—2 of Figure 1 showing the overlapped end of two of the shoes;

Figure 3 is an elevation of the overlapped parts of two of the shoes, looking in the di-

rection of the arrows 3—3 in Figure 1 but with the drum removed;

Figure 4 is a section through one of the shoes on the line 4—4 of Figure 1;

Figure 5 is a section corresponding to Figure 2, but showing a different construction of the pivoted parts of the shoes;

Figures 6 and 7 are views corresponding to Figure 3, but broken away to show different constructions of the pivoted parts of the shoes;

Figure 8 is a section corresponding to Figures 2 and 5, but showing an arrangement with only one fixed anchor instead of two;

Figure 9 is a vertical section, corresponding to Figure 1, but showing a brake with the anchorage means of Figure 5 and with the shoe connection of Figure 7; and

Figure 10 is a partial section on the line 10—10 of Figure 9.

The brake selected for illustration in Figures 1—4 includes a drum 10, the open side of which may be closed by a suitable backing plate 12, within which are arranged a plurality of arcuate and substantially rigid brake shoes 14, 16 and 18. The shoes 14 and 18 are arranged to be forced apart against the resistance of a return spring 20 by means 80 such as a cam 22, in order to apply the brake, shoe 13 being arranged to turn a short distance with the drum when applied to apply shoe 16 against the resistance of an auxiliary return spring 24.

According to an important feature of the present invention, the stiffening web of shoe 16 is arranged at one side of the central plane of the brake, while the stiffening webs of the shoes 14 and 18 are arranged at the 90 opposite side of the central plane of the brake so that they may overlap opposite ends of the stiffening web of shoe 16. The overlapped portions of the stiffening webs of shoes 16 and 18 are connected by suitable 95 means such as a pivot 26 to permit the operation of shoe 16 by movement of shoe 18 as described above.

The overlapped ends of shoes 14 and 16 are arranged to be anchored on the backing plate 100 12 or an equivalent support, the shoe 14 being anchored on a pivot 28 passing

through a relatively large opening 30 in the stiffening web of shoe 16, while the shoe 16 is anchored on a pivot 32 passing through a relatively large opening 34 in the stiffening web of shoes 14.

I prefer to make the shoes of pressings or stampings of sheet metal, generally L-shaped in cross section, and riveted or otherwise secured together back to back as shown in Figure 4. The outer flanges 36 and 38 together form a substantially cylindrical friction face for the shoe, which may be provided with suitable lining material 40 (omitted in Figure 3). Flanges 36 and 38 are of unequal width so that the inner flanges 42 jointly form a stiffening web for the shoe which is in substantially the same plane from one end of the shoe to the other but which is displaced at one side of the central plane of the shoe. If desired, short stiffening flanges 44 may project laterally from the inner edges of the flanges 42. All three of the shoes are of the same general construction, although the stiffening web formed by flanges 42 of shoe 16 is on the opposite side of the central plane of the shoe from the corresponding webs of shoes 14 and 18.

In Figures 5-8 are shown arrangements designed to permit the stiffening webs to be closer to the central plane of the shoes. In Figure 5, shoe 114 is anchored on a pin 128 passing through a relatively large opening 130 in shoe 116, while shoe 116 is anchored on a pin 132 passing through a relatively large opening 134 in shoe 114, in the same general manner as before. However, each shoe has its inner stamping left straight, with the bearing for the anchor pin formed entirely in the outer stamping, preferably as an integrally-drawn tubular boss or bushing 50. Preferably each boss 50 is conical throughout most of its length, with a short cylindrical part at its outer end cooperating with the hole in the inner stamping to give spaced bearings on the anchor pin.

As shown in Figure 6, the same arrangement may be used for the pivotal connection of shoes 116 and 118 on a pivot connection 126, with a fiber washer 52 inserted between the shoes if desired. Connection 126 is shown with a grooved head interlocking with a grooved adjustable eccentric stop 54 carried by the backing plate 56.

As shown in Figure 7, another manner of bringing the stiffening webs nearer together is to form one shoe (e. g. shoe 216) with oppositely-drawn bosses 58 providing spaced bearings on the pivot connection 226, while the other shoe (e. g. shoe 218) has welded or riveted or otherwise secured thereto a separate bearing member or fitting 60 sleeved on the connection (or on the anchor), and dished to clear the boss 58 on that side.

In Figure 8 is shown an arrangement sim-

ilar to that of Figure 5, except that shoe 314, corresponding to shoes 14 and 114, is not mounted directly on a fixed anchor, but transmits its braking torque through shoe 316 to anchor 332, being connected to shoe 314 by a pivot connection 328, shown as having an enlarged head 62 slidably engaging backing plate 56.

While several illustrative embodiments have been described in detail, it is not my intention to limit the scope of the invention to those particular embodiments, or otherwise than by the terms of the appended claims.

I claim:

1. A brake including a pair of shoes, each of which is formed with a cylindrical arcuate friction portion and with a stiffening web projecting radially of the shoe and arranged between the edges of the friction portion and at one side of the center of the shoe and which is in substantially the same plane from one end of the shoe to the other, the stiffening web of one shoe being on the opposite side of the central plane of the shoe from the other, and the stiffening webs of the two shoes overlapping each other at the adjacent ends of the shoes, together with means for taking braking torque from the overlapped parts of the stiffening webs.

2. A brake comprising, in combination, a pair of shoes, each of which is formed of two pressed metal stampings generally L-shaped in cross-section and arranged and secured back to back, the oppositely extending outer flanges of the stampings forming a generally cylindrical friction face for the shoe and being of unequal width so that the stiffening web formed by the other flanges of the stampings is between the edges of the shoe but at one side of the center of the shoe, the stiffening web of each shoe being in substantially the same plane from one end of the shoe to the other, and the stiffening web of the one shoe being on the opposite side of the central plane of the shoe from the stiffening web of the other shoe and the stiffening webs of the two shoes being arranged to overlap each other at the adjacent ends of the shoes.

3. A brake comprising, in combination, a central shoe having a stiffening web at one side of the central plane of the shoe, and two other shoes arranged at opposite ends of the central shoe and having their stiffening webs on the opposite side of the central plane of the central shoe and arranged to overlap the ends of the stiffening web of the central shoe, the stiffening web of the central shoe being in substantially the same plane from one end of the shoe to the other.

4. A brake comprising, in combination, a central shoe having a stiffening web at one side of the central plane of the shoe, and two other shoes arranged at opposite ends of

the central shoe and having their stiffening webs on the opposite side of the central plane of the central shoe and arranged to overlap the ends of the stiffening web of the central shoe, the stiffening web of each end shoe being arranged in substantially the same plane from one end of the shoe to the other.

5. A brake comprising, in combination, a plurality of shoes, each of which is built up 10 of two sheet metal stampings generally L-shaped in cross-section and secured back to back with the outer flanges forming a substantially cylindrical friction face and being of unequal width so that the stiffening web 15 formed by the straight flanges is displaced at one side of the central plane of the shoe and is in substantially the same plane from one end of the shoe to the other, the stiffening web of the central shoe being at one side 20 of the central plane of the shoes and the stiffening webs of the end shoes being on the opposite side of the central plane of the shoes and overlapping opposite ends of the stiffening web of the central shoe.

25 6. A brake shoe comprising two pressed metal stampings generally L-shaped in section secured together back to back with the outer flanges forming a generally cylindrical friction face and being of unequal width, 30 and with the inner flanges which are secured together forming a stiffening web for the shoe which is displaced at one side of the central plane of the shoe from one end of the shoe to the other.

25 7. A brake shoe of pressed metal having two flanges between its edges forming a stiffening web, and one of which flanges has an outwardly-drawn tubular boss forming:

a bearing pivotally to engage a pivot, and the other of which is provided with an opening in its own plane which is coaxial with respect to said boss and which forms a second bearing for said pivot. 40

8. A brake comprising, in combination, two over-lapping shoes, each having two 45 flanges forming a stiffening web, the flange of each shoe next the other shoe being substantially plane at least at the end of the shoe, to permit bringing the overlapped parts of the shoes close together, and with 50 the flange away from the other shoe drawn out to form a tubular boss to provide a pivot bearing at that side of the stiffening flange.

9. A brake comprising, in combination, two over-lapping shoes, each having a stiffening web, the side of each web next the other shoe being substantially plane at least 55 at the end of the shoe, to permit bringing the overlapped parts of the shoes close together, and with the side away from the other shoe projecting out to form a perforated boss to provide a pivot bearing at that side of the stiffening flange. 60

10. A brake comprising, in combination, a pair of overlapping shoes, each having a pair 65 of flanges forming a stiffening flange, the flanges of one shoe being drawn out in opposite directions to form oppositely-directed tubular coaxial bosses to be sleeved on a pivot pin, and with the other shoe being provided with a separate fitting to be sleeved on said pin and dished to clear said boss on that side. 70

In testimony whereof, I have hereunto signed my name.

ADIEL Y. DODGE.
